US0D1060279S

(12) **United States Design Patent** (10) Patent No.: **US D1,060,279 S**
(45) Date of Patent: ** Feb. 4, 2025

(54) **UTILITY METER DUAL TRANSCEIVER BOARDS**

(71) Applicants: **Michael Lee Gregory**, Hallsville, TX (US); **Jason Edward Pintok**, Lake Mary, FL (US); **Ian Harvey**, Bristol (GB)

(72) Inventors: **Michael Lee Gregory**, Hallsville, TX (US); **Jason Edward Pintok**, Lake Mary, FL (US); **Ian Harvey**, Bristol (GB)

(**) Term: **15 Years**

(21) Appl. No.: **29/792,396**

(22) Filed: **Mar. 28, 2022**

(51) LOC (15) Cl. **13-03**

(52) U.S. Cl.

USPC **D13/182**; D13/184

(58) Field of Classification Search

USPC D13/118, 120, 121, 123, 131, 160, 162, D13/182, 184, 199

CPC G01R 21/133

(57) **CLAIM**

The ornamental design for the utility meter dual transceiver boards as shown and described.

DESCRIPTION

FIG. 1 is a right side plan view thereof;

FIG. 2 is a left side plan view thereof;

FIG. 3 is a right side plan exploded view thereof;

FIG. 4 is a backside plan view thereof;

FIG. 5 is a front-side plan view thereof;

FIG. 6 is a front-side perspective view thereof;

FIG. 7 is a backside plan view of the LTE board thereof;

FIG. 8 is a front-side plan view of the LTE board thereof;

FIG. 9 is a backside plan view of the 450 MHz board thereof; and,

FIG. 10 is a front-side plan view of the 450 MHz board thereof.

The broken lines in the drawings illustrate portions of the utility meter dual transceiver board, which form no part of the claimed design.
